UNITED STATES PATENT OFFICE.

SILVESTRO MILANO, OF NEW YORK, N. Y., ASSIGNOR OF ONE-HALF TO GEORGE E. H. WERHAM, OF SOUTH NYACK, NEW YORK.

DETACHABLE HEEL.

1,212,796.

Specification of Letters Patent. Patented Jan. 16, 1917.

Application filed December 13, 1911. Serial No. 665,464.

To all whom it may concern:

Be it known that I, SILVESTRO MILANO, a citizen of the United States, residing in the city of New York, borough of the Bronx, 5 county and State of New York, have invented a certain new and useful Detachable Heel, of which the following is a specification.

This invention is a detachable heel or sole 10 for all kinds of foot wear, more particularly for boots and shoes.

The object of the invention, broadly stated, is to replace a worn heel-lift or sole 15 of a boot or shoe by a new layer of material in an easy and expeditious manner, without the necessity of skilled labor, and, further, to hold the new layer of material securely in place or against any tendency to become disconnected from the boot or shoe,

20 The invention enables the wearer of a boot or shoe to detach the bottom layer of a sole or heel which has worn down either in the middle or on the outer edge, and to replace the same by a new or fresh layer of any suitable 25 material, the operations being performed without requiring the services of a skilled workman.

Among the novel features of the invention may be mentioned the following. First, 30 novel attaching means which preclude either a lateral or separating movement of the replaced member with reference to the fixed part of the sole or heel; second, a novel means for telescoping the attaching members together prior to locking, and, third, 35 novel means for anchoring the material to one of the attaching members.

Other features of the invention will be apparent from the hereinafter detailed 40 description.

In the accompanying drawings, I have illustrated different practical embodiments of the invention, but the constructions shown therein are to be understood as illustrative, 45 only, and not as defining the limits of the invention.

Figure 1 is a side elevation, partly in section, showing the lift applied to the heel of an ordinary shoe. Fig. 2 is a bottom plan 50 of Fig. 1 with the lift member removed. Fig. 3 is a front elevation of the member shown in Fig. 2. Fig. 4 is a plan view of the heel lift of Fig. 1. Fig. 5 is a transverse section through the heel lift on the 55 line 5—5 of Fig. 4. Fig. 6 is a longitudi-

nal sectional view through a heel and lift, wherein the relation of the plates to the shoe is the reverse to that shown in Fig. 1, the section being taken on the line 6—6 of Fig. 7. Fig. 7 is a bottom plan of the heel of Fig. 6, a portion thereof being broken away to show the protruding or end locking flanges which engage the lift. Fig. 8 is a plan view of the heel lift of Figs. 6 and 7. Fig. 9 is a front elevation of the heel lift of Fig. 8. 60 Figs. 10 and 11 are a longitudinal section through a complete heel, and a plan of the heel, respectively, showing one of the plates divided into two sections, the plane of the section of Fig. 10 being indicated by the 65 dotted line 10—10 of Fig. 11. Fig. 12 is a transverse section through the upper co-operating member of Figs. 10 and 11, and on the dotted line 12—12 of Fig. 11. Fig. 13 is a longitudinal section through a heel 70 showing a composite lift applied to the heel. Fig. 14 is a top plan view of the bottom co-operating plate of Fig. 13, and Fig. 15 is a bottom plan view of the plate of Fig. 14.

This invention is illustrated as applied 75 to the heel of a shoe.

Referring more particularly to Figs. 1 to 5, the invention comprises interlocking members in the form of plates A, B which co-operate with each other to secure the heel lift to the shoe. Plate A is constructed of any suitable material, preferably of sheet metal which may be tempered if so desired, and this plate is provided along its edge with an inturned flange 20, the walls of 80 said flange being integral with the plate and bent preferably at an oblique angle thereto, thereby forming a chamber between the plate and the portion of the heel or lift to which the plate is applied. This flange 85 extends substantially around the plate except at the front edge thereof, where the flange is omitted to permit of the insertion of a filler π , of any suitable material, such as leather, wood or a composition of material into the chamber formed by the flanges 90 20 of the plate, the filler serving as a core or support for plate A. This plate A, may be provided, also, with lips 21, which lips are integral with the inturned flange 20, 95 and are bent at an angle to said flange so that the lips lie in a plane parallel to the plate A. The core or filler π is inserted into plate A, and it is retained between said plate and lips 21 by suitable securing means, 100 105 110

such as screws 22, which pass through plate A, filler α , lips 21, and into the main portion of the heel C, thereby rigidly securing plate A to the shoe. It is obvious, however, that these lips can be omitted without affecting the operation of the device.

- 5 Coöperating plates A, B may be of any desired shape or contour, but in the drawings they are shown as having straight sides, 10 with one end substantially semi-circular and the other end of a shape to conform to the front edge of an ordinary heel lift. The plate A is provided with an aperture 23, preferably in the semi-circular part of the 15 plate and extending into the flange 20, the purpose of which aperture 23 will be presently explained. At the other end of plate A, preferably about opposite to the aperture 23, said plate is provided with parallel slits 24, to produce a tongue 25. A stud 26 is 20 integral with the tongue, said stud being below the horizontal plane of plate A. This stud 26 and tongue 25 operate as a spring latch to lock the plates A and B in their 25 assembled positions, the straight edge of stud 26 engaging with a straight edge of an aperture 27 in plate B, thereby preventing accidental removal of plate B from plate A. It is obvious that the latch may 30 be reversed as to plates A and B without affecting the operation of the device. However, the latch may be of any other desired form, as in Fig. 15 the stud 26 is shown as substantially triangular.
- 35 Plate B in Figs. 4 and 5, is applied to the heel lift D. This plate B is similar in general appearance to plate A in that it is provided with straight sides, one end semi-circular and the other end slightly curved to 40 conform to the shape of the heel. This plate is provided with a flange 28 substantially around the plate except at the slightly curved edge thereof, and this flange is bent at an oblique angle to the plate, as in the 45 case of plate A, so that when it is desired to assemble plates A and B to the position shown in Fig. 1, the flange 28 of plate B will inclose flange 20 of plate A, said plate B thereby substantially inclosing plate A. 50 The coöperating flanges 20, 28 operate to prevent movement of the heel lift relative to the shoe, *i. e.*, the two flanges preclude a lateral separation of the lift from the heel.
- 55 Any suitable means may be employed for attaching plate B to the heel lift, but in Figs. 4 and 5 I have shown prongs 29 which are integral with plate B, said prongs being driven into the material composing the heel lift. Plate B is provided, also, with a stud 30 which is adapted to engage with the aperture 23 of plate A, said stud and slot serving as a thrust device. This thrust device 60 coöperates with the two plates A, B, and 65 operates to take away a part of the strain

brought upon the flanges by the twisting movement exerted by one part of the heel upon the other part of the heel. This thrust device, therefore, relieves the flanges from undue strain when the heel is in use. 70 It also precludes the flanges 20, 28 from becoming accidentally separated or torn apart at the rear of the heel, such for example as when a sudden vertical strain is exerted upon the movable part of the heel with relation to the fixed part of the heel.

In Figs. 6, 7, 8 and 9, the plate A is united to the heel lift D, and plate B is attached to heel C. The plate A of these figures is similar in substantial respects to plate A of Fig. 80 2, except that the plate A of Fig. 8 is provided with stud 30, instead of aperture 23, and the securing lips 21 for the filler α are omitted. Said plate A is provided, also, with protruding flanges 31 which are integral with, and in the same horizontal plane as, said plate A, said flanges operating to prevent the corners of the lift from becoming separated from the heel. Depending from the slightly curved edge of said 85 plate A, and the protruding flanges 31, is a depending flange (not shown) which is adapted to fit snugly against the heel lift D, said depending flange being integral with plate A and flanges 31, and depending 90 at a right angle therefrom. If desired, the lift may be cut away sufficiently to permit the depending flange to lie flush with the front wall of heel C and lift D. The protruding flanges 31 may extend from the edge 100 of plate A to the outer edge of heel D, as shown in Fig. 8, or said flange may be shorter, as in Fig. 11. The protruding flanges 31 fit into slots 32 in the heel C, Fig. 7, and serve to prevent the separation of the 105 heel lift D from the heel C at the corners of the lift. Flanges 31 and stud 30 operate to preclude any separating movement, or any lateral movement, respectively, of the lift with reference to the fixed part of the 110 shoe.

The construction of Figs. 10, 11 and 12 is substantially similar to the construction of Figs. 6 and 7, the plate B' of Fig. 10 being substantially similar to the plate B of 115 Figs. 4 and 7, but the other plate which co-
operates with plate B' is divided so as to produce two sections A', A², to facilitate manufacture of the device and its easy adjustment of the parts. The part A' is constructed of sheet metal, similar to plate A of Fig. 2, but the part A² may be made of solid metal to produce a substantial anchorage for attaching the lift to the heel. In this construction, the section A' overlaps a 120 portion of the section A², and said plate A' is provided with suitable ears α^2 through which suitable fastening means, such as screws, are passed to secure both sections 125 A', A² to the heel C. The protruding 130

flanges 31 in this form of the device are integral with the section A², and, as shown, do not extend to the outer edge of the heel lift D, but terminate at a point substantially midway between the edge of the lift and the edge of plate A².

In Figs. 13 14 and 15, the plate A³ of the device is substantially similar to plate A of Fig. 2, and is secured directly to the heel C, as shown in Fig. 13. Coöperating plate B³ is similar in many respects to plate B of Fig. 4, except that plate B³ is designed to be used with a lift of special material, such as wood, rubber, concrete preparation, or other composition of materials. When the lift is made of rubber, or a composition, the plate B³ is molded into the material, thereby embedding the anchoring plate B³ into the material composing the lift. This plate is provided with upstanding prongs 33 of any desired form which are stamped from the plate and bent upwardly and outwardly to provide means for anchoring the plate into the material of the lift. In addition to the prongs 33 for engaging the lift, the plate B³ may be, and preferably is, provided with lugs 34, 35 of any suitable shape or contour, said lugs being stamped from the main portion of the plate and bent outwardly so that they radiate from the plate, as shown in Figs. 14 and 15. These lugs 34, 35 serve as additional anchoring means around which the composite lift is molded. The prongs 33 and lugs 34, 35 are so securely embedded in the material of the lift, so that should the wearer of the shoe subject the heel to a severe blow or accident, the lift will not be torn from the plate.

In applying the device to an ordinary shoe, one of the plates, for instance, plate A, is secured to the heel C by any suitable fastening means, such as the screws 22. The slightly curved end of plate B, with the lift D attached thereto, is slipped over the semi-circular end of plate A so that the flange 28 of plate B will engage and inclose flange 20 of plate A. The lift is now pushed toward the toe of the shoe, the flanges 20, 28 operating to guide the movement of the lift until the slightly curved front edge of the lift registers with the slightly curved front edge of the heel, whereupon the stud 30 of plate B will enter slot 23 of plate A, and protruding flanges 31 will have entered the slots 32 in lift D. The spring latch 26 snaps into engagement with the slot 27 as soon as the lift has reached the end of its forward movement, and said lift is thereby secured against accidental removal or displacement from the heel in any direction.

To remove the lift D from heel C, for the purpose of replacing an old lift by a new one, or to change the lifts to different shoes, it is only necessary to depress tongue 25, thus disengaging stud 26 from slot 27,

whereupon the lift may be readily removed from the heel.

The present application, so far as it relates to Figs. 1 to 5 is, in part, a continuation of my former application Serial No. 360,892 filed March 6, 1907 and which eventuated in Letters Patent No. 995,703, granted to me on June 20, 1911.

Having thus fully described the invention, what I claim as new, and desire to secure by Letters Patent is:

1. In a heel for footwear embodying a fixed part and a movable part, coöperating plates one on the fixed part and the other on the movable part, the area of said coöperating plates being less than the area of the parts on which they are respectively positioned and the marginal edge of each plate being within the margin of the part to which the plate is applied, resilient means integral with one of said plates for detachably coupling the plates, and means coöperating with said plates and positioned exteriorly thereto for relieving said coupling means from a substantial part of the strain exerted by one part upon the other part due to a twisting movement of one part relatively to the other, whereby said plates are precluded from becoming accidentally separated by twisting strains.

2. A heel for footwear embodying a fixed part and a movable part, coöperating plates one of which is on the fixed part and the other on the movable part, one of said plates having a chamber, each plate being provided with inturned flanges, one of which plates is arranged to slide within the other plate, and a core or filler occupying said chamber of one plate and precluding the plate from collapsing under the pressure and strain to which the plate is subjected when in use.

3. A heel for footwear embodying a fixed part and a movable part, coöperating plates, one of which is attached to the fixed part and the other plate is attached to the movable part, one of said plates being flanged and united to one of said parts to produce an intervening chamber, and a removable core or filler occupying said chamber and supporting said flanged plate against collapsing under the pressure and strain to which the plate is subjected when the device is in use.

4. A heel for footwear embodying a fixed part and a movable part, and coöperating plates arranged to detachably secure the movable part to the fixed part, one of which plates is attached to the movable part, the other of said plates being composed of two sections detachably united together, said sections being attached to the fixed part of the heel, one of said sections having a core integral therewith, and the other of said sections having a removable core.

5. A heel for footwear embodying a fixed part and a movable part, coöperating plates, one of which is attached to the fixed part, and the other plate to the removable part, 5 said plates being provided with coöperating inturned flanges arranged to secure the movable part to the fixed part, said fixed plate being chambered, a core filling the chamber of said plate, the flange of one 10 plate being provided with a slot, and a thrust stud on the other plate, said thrust stud fitting in said slot so as to relieve one plate from a part of the strain brought upon the flanges by a twisting movement 15 of one part of the heel relatively to the other part of said heel.

6. A heel for footwear embodying a fixed part and a movable part, coöperating plates having inturned flanges, one of which plates 20 being attached to the fixed part and the other to the removable part, one of said plates having a slot, one of said plates being provided with outwardly directed flanges at the corners thereof, said corner flanges 25 fitting against the front of the fixed part

and a stud engaging said slot and operating to relieve the various flanges from strain due to the twisting movement of one part of the heel upon the other part of the heel.

7. A heel for footwear embodying a fixed part and a movable part, coöperating members having means for detachably coupling them together, one of which members is attached to the fixed part of the heel, and 35 the other member to the movable part, and outwardly directed flanges extending from the respective corners of one member and engaging with slots formed in the fixed part of the heel for precluding a relative 40 movement between the corners of the movable and fixed parts of the heel.

In testimony whereof I have signed my name to this specification in the presence of two subscribing witnesses.

SILVESTRO MILANO.
